SUPPORT ROLLER FOR PRINTED WEBS

Bernard Offen, Chicago, Ill.

Application January 11, 1951, Serial No. 205,485

4 Claims. (Cl. 34—240)

1

This invention relates to support rollers for printed webs and more particularly to a roller having spaced portions adapted to support a printed web passing thereover without smearing the ink or making the printed web dirty.

In some web offset printing presses, it is common practice to print on both sides of the paper web at the same time. When it is necessary to pass the printed web through a dryer, it will be appreciated it is extremely difficult to keep the paper clean and to prevent the ink from smearing during its passage into and through the dryers since contact by the printed surfaces with rollers over which it passes smears the wet ink and spreads the smeared ink over the paper web. Another disadvantage rises due to the fact that a greater number of lead pages are being printed so that margins between the pages are made smaller or eliminated thereby increasing the chances of smearing wet ink since it is necessary that the so-called marginal rollers come in contact with the printed surfaces rather than into contact with unprinted portions of the web.

The chief object of the present invention is to provide a support roller for a printed web which greatly decreases the chances of smearing wet ink and which assists greatly in maintaining a clean sheet.

An object of the present invention is to provide a support roller for use in combination with a dryer which is provided with a surface which permits a paper web carrying wet ink to pass into and through the dryer without substantial smearing of the ink.

A further object is to provide a marginal roller carrying ring members adjustable longitudinally of the roller so that such members may be placed in a position to support a printed web without materially smearing the printed surfaces of the web. Other objects of the invention will be readily perceived from the following description.

The attached drawings illustrate a preferred embodiment of my invention, in which

Figure 1 is a diagrammatic view of a dryer provided with web support rollers of the present invention;

Figure 2 is a view partly in section and partly in elevation of a roller carrying the support rings of the present invention;

Figure 3 is an exaggerated view in elevation of a portion of a roller showing the manner in which the rings are secured in place;

Figure 4 is a sectional view drawn to an enlarged scale of the ring covering or surfacing material;

Figure 5 is a view partly in elevation and partly in section of a modified roller;

Figure 6 is a view partly in elevation and partly in section of a marginal roller;

Figure 7 is a view in elevation of the end of the roller shown in Figure 6; and

Figure 8 is a fragmentary sectional view illustrating a modified marginal roller.

Referring to the drawings, there is shown a dryer 2 having a drying chamber 3 into which printed webs 4 are passed to dry the ink and having at least one chilling roll 5 for each web 4 to cool the heated web prior to its passage to the folder or other equipment. Any suitable means may be provided to heat the printed webs in the dryer as is well known.

It will be appreciated it is necessary to pass the printed web, printed on one or both surfaces, over idler rolls before the ink on the web is dry. Any or all of the idler rolls 6 shown in Figure 1 may be formed in accordance with the present invention.

Referring to Figures 2, 3, and 4, roll 6 comprises a shaft 7 having end portions 8 adapted to be journaled in suitable bearings. A plurality of rings 9 are spaced longitudinally of shaft 7 to support the printed web. Each ring 9 consists of a perforated metal strip 10 having perforations 11 therein, the perforations extending beyond the plane of the strip 10 so that the walls forming the perforation serve to support the printed web; thus only a minor portion of each ring contacts the printed web thereby reducing smearing of wet ink to a minimum and assisting in keeping the web clean. Preferably, the perforations 11 are formed by punching spaced portions of strip 10 to raise the walls of each perforation above the plane of the ring. The rings 9 are pinned as shown in Figure 3 at 12 to secure them to shaft 7. The joints of the rings are staggered and if desired the rings may be pinned to the shaft at two additional places 120° on each side of the joint.

In Figure 5, a modified support roll is shown. A shaft 15 carries a plurality of sleeves 16 attached to the shaft by set screws 17 so that the sleeves may be moved longitudinally of the shaft. A recess 18 is provided in each sleeve 16 which extends circumferentially about the sleeve. Perforated metal covering 19 as described above is placed in the recess, the raised portions 20 of the covering extending beyond the plane of the sleeve to support the printed web.

In Figures 6 and 7, there is shown a portion of a marginal roller provided with the supporting surface of the present invention. The roller consists of a shaft 20 having a plurality of rings or sleeves 21 spaced therein. The rings 21 are attached to shaft 20 by means of set screws 22 thereby enabling the rings 21 to be placed in any desired position longitudinally of the shaft. Each ring 21 carries the perforated metal covering 23 above described, the ends 24 of the covering 20 being placed in a slot 25 in the ring and being

held therein by a wedge 26. The marginal roller described may be placed in positions in which the printing is light thereby reducing the tendency to mark the printed paper to a minimum.

In Figure 8, there is shown a modified marginal roller. The ring 21 shown has its circumferential surface recessed as shown at 27, the perforated metal covering 23 being placed in the recess, the walls of the perforations extending beyond the plane of the ring 21 to support the printed web. In other respects, the roller of Figure 8 is similar to the roller shown in Figures 6 and 7.

The present invention provides a dryer arrangement for printed webs which is so constructed as to prevent the ink from smearing where it contacts the support rollers. The support roller is so designed that only a minimum amount of its surface contacts the printed web. The rollers are provided with contact surfaces which are adjustable longitudinally of the shaft. Such contact surfaces afford ample support for the printed sheet and permit a commercially clean sheet to be obtained.

Use of the support rollers of the present invention permits a longer drying time since the web may make a number of passes through the dryer thus permitting drying at lower temperatures and higher speeds while obtaining a clean sheet and eliminating smearing of the ink. The marginal rollers provided by my invention are economical, the supporting surfaces being adjustable to permit placement in the margins of the printed paper or between the margins while providing adequate support for the paper ink and reducing to a minimum any tendency to mark the sheet.

While I have described a preferred embodiment of my invention, it will be understood my invention is not limited thereto since it may be otherwise embodied within the scope of the following claims.

I claim:

1. In combination with a dryer through which a web printed on one or both sides passes, at least one support for the printed web which comprises a shaft, a plurality of metal sleeves mounted on the shaft, each metal sleeve being adjustable longitudinally of the shaft and having a recess formed in its circumferential surface, and a covering placed in the recess having spaced portions

raised beyond the periphery of the covering, the raised portions of the covering rising above the external peripheral surface of the sleeve.

2. A support roller for printed webs which comprises a shaft, a plurality of metal sleeves mounted on the shaft, a set-screw securing each sleeve to the shaft thereby permitting each sleeve to be moved longitudinally of the shaft, each sleeve having a recess formed in its circumferential surface, a covering placed in the recess, the covering having perforations formed by punching spaced portions thereof to raise the walls of each perforation beyond the periphery of the covering, the raised portions of the covering rising above the external peripheral surface of the sleeve and forming a support for the printed web.

3. A marginal roller for use in web offset printing presses which comprises a shaft, a plurality of metal sleeves mounted on the shaft, each sleeve being adjustable longitudinally of the shaft, each sleeve having a recess therein extending circumferentially thereof, and a covering placed in the recess having raised portions thereon extending beyond the peripheral surface of the sleeve to form a support for the printed web.

4. A marginal roller according to claim 3 in which the raised portions comprise perforations formed by punching spaced portions of the covering to raise the walls thereof above the peripheral surface of the sleeve.

BERNARD OFFEN.
